PAPER STOCK MACHINE

Maxine Chevrier, Harrisville, N. Y.

Application May 25, 1940, Serial No. 337,312

2 Claims. (Cl. 137—78)

The present invention relates to new and useful improvements in paper stock machines and has for its primary object to provide, in a manner as hereinafter set forth, an apparatus of this character embodying a novel construction, combination and arrangement for automatically regulating the consistency of the stock.

Another important object of the invention is to provide a paper stock machine of the aforementioned character embodying unique means whereby the automatic regulating mechanism may be conveniently adjusted as desired.

Other objects of the invention are to provide a paper stock machine of the character described which will be comparatively simple in construction, strong, durable, highly efficient and reliable in use, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a machine constructed in accordance with the present invention.

Figure 2 is a top plan view thereof.

Figure 3 is a view in vertical longitudinal section, taken substantially on the line 3—3 of Figure 2.

Figure 4 is an end elevational view, a portion of the water control valve being broken away in section.

Figure 5 is a view in side elevation of the adjustable, spring controlled regulating device or unit, the spring and an adjacent portion of the tank being shown in section.

Figure 6 is a cross sectional view through the machine, taken substantially on the line 6—6 of Fig. 1.

Referring now to the drawings in detail, it will be seen that the embodiment of the invention which has been illustrated comprises an elongated tank 1 of suitable dimensions, said tank being open at its top. Mounted at longitudinally spaced points in the tank 1 are transversely extending partitions or dams 2 providing a stock inlet chamber 3, an agitator chamber 4, a delivery chamber 5 and an outlet or overflow chamber 6. It will be observed that the chambers 3 to 6, inclusive, are provided with rounded corner portions, as at 7, to prevent the accumula-

tion in the corners of stagnant stock. An inlet pipe 8 communicates with the chamber 3 and an outlet pipe 9 communicates with the chamber 6.

5 Mounted transversely in the tank 1 in the agitator chamber 4 thereof is a shaft 10. The shaft 10 has fixed thereon an agitator 11 for operation in the chamber 4. Referring now to Fig. 5 of the drawings, it will be observed that the shaft 10 includes a threaded end portion which projects through the front wall of the tank 1. Mounted on this end portion of the shaft 10 is an overload releasing clutch which is designated generally by the reference numeral 18. The clutch 18 includes complementary cam members 14 and 15, the former being loose on the shaft 10, the latter being fixed on said shaft. Fixed on the outer end of the clutch member 14 is a gear 12. A circumferential groove or channel 16 is provided in the clutch member 14, the purpose of which will be presently set forth. A coil spring 17 is mounted on the shaft 10 and engaged with the member 15, thus releasably connecting the gear 12 to the shaft 10 for driving said shaft. 15 Hand operated nuts 18 are threaded on the shaft 10 for regulating the tension of the coil spring 17. Attention is here called to the fact that the gear 12 is comparatively wide.

20 Mounted transversely in suitable bearings 19 on one end of the tank 1 are upper and lower shafts 20 and 21, respectively. Fixed on the shafts 20 and 21 are oppositely tapered pulleys 22 having trained thereover a laterally movable endless belt 23. The reference numeral 24 designates a screw shaft which is journaled in suitable bearings 25 on this end of the tank 1. Threadedly mounted on the screw shaft 24 is a shifter 26 for moving the endless belt 23 laterally in either direction for varying the speed of the upper or driven pulley 22 relative to the lower or drive pulley 22. A hand wheel 27 is provided on one end of the screw shaft 24 for moving the shifter 26. Suitable guides 28 are provided on the tank 1 for the shifter 26.

25 Fixed on one end portion of the shaft 21 is a stepped pulley 29 for receiving an endless drive belt from a conventional paper machine. Fixed on the other end portion of the shaft 21 is a pulley 30. The reference numeral 31 designates a pulley which is fixed on a stub shaft 32 rotatably mounted on the front of the tank 1. An endless belt 33 is trained over the pulleys 30 and 31. Fixed on the shaft 32 is a comparatively small gear 34 which drives the gear 12.

30 Mounted transversely on top of the tank 1

above the chamber 4 is a water tank or reservoir 35. Mounted in the lower portion of the water tank 35 and extending substantially the length thereof is a slideable discharge valve 36. Mounted for swinging movement on the front of the tank 1 is a lever 37. The pivotal mounting of the lever 37 may be adjusted, as at 38, for regulating the stroke of said lever. One end portion of the lever 37 is operatively connected at 39 to an end portion of the water control valve 36. On the other end of the lever 37 is a yoke or fork 40 which is engaged in the groove 16 for actuation by the slideable clutch member 14.

Mounted at an inclination in the tank 1 and extending downwardly into the chamber 5 thereof is a stock delivery conveyer which is designated generally by the reference numeral 41. It will be observed that the conveyor 41 extends through the rear wall of the tank 1. The conveyor 41 includes a tubular housing 42 in which 20 a worm 43 is operable. Fixed on the upper end portion of the shaft 44 of the worm 43 is a pulley 45. The pulley 45 is driven by an endless belt 46 from a pulley 47 on one end portion of the shaft 20.

It is thought that the operation of the machine will be readily apparent from a consideration of the foregoing. The water control valve 36 of the tank 35 is normally closed, as seen in Fig. 4 of the drawings. With the stock in the agitating chamber 4 of the correct consistency, the shaft 10 is driven from the paper machine through an endless belt trained over the stepped pulley 29, the shaft 21, the pulleys 30 and 31, the belt 33, etc., the water control valve 36 remaining closed. However, if the stock is too heavy and the load on the shaft 10 is sufficiently great to compress the spring 17, the cam clutch member 14 will be caused to reciprocate on the shaft 10, thereby opening and closing the valve 36 through the lever 37 for intermittently discharging water by gravity into the agitating chamber 4 from the tank 35. This continues until the stock has been thinned to the desired consistency and when this condition is reached the load on the shaft 10 will have been reduced sufficiently to permit the coil spring 17 to keep the clutch 48 closed thereby again permitting the gear 12 to drive the shaft 10 and shutting off the water from the tank 35. The stock flows from the chamber 4 into the chamber 5 from which it is delivered to the usual paper machine by the spiral or worm conveyor 41. The speed of operation of the conveyor 41 may be controlled as desired by shifting the endless belt 23 in either 55 direction on the pulleys 22.

It is believed that the many advantages of a paper stock machine constructed in accordance with the present invention will be readily understood and although a preferred embodiment of the apparatus is as illustrated and described, it is to be understood that changes in the details of construction and in the combination and arrangement of parts may be resorted to which will fall within the scope of the invention as claimed.

5 What is claimed is:

1. In a paper stock machine, a mixing chamber, a shaft passing transversely therethrough with one end extending from the chamber, agitator blades connected with the shaft and located in the chamber, a gear loosely located on the projecting end of the shaft, slip clutch means for connecting the gear with the shaft; a drive shaft, a gear thereon meshing with the first-mentioned gear, water supply means in communication with the chamber, a valve for controlling communication between the supply and the chamber, said clutch parts slipping on each other when the consistency of the stock in the mixing chamber reaches a certain degree to stop 25 rotary movement of the blades and means between the valve and the clutch means for opening the valve when the clutch parts are slipping on each other and for closing the valve means when the clutch parts are rotating the shaft from the gear.

2. In a paper stock machine, a mixing chamber, water supply means above the chamber and in communication therewith, a valve for controlling the communication between the supply 35 and the chamber, a shaft passing through the chamber and having one end projecting therefrom, agitator blades on the shaft within the chamber, slip clutch parts on the projecting end of the shaft, one part being connected with the shaft and the other rotatably arranged on the shaft, a gear connected with the rotatably arranged clutch part, spring means on the shaft for holding the parts in engagement, a lever having one end engaged by the rotary clutch part 45 and its other end connected with the valve, the lever holding the valve closed when the clutch parts are in operated position but opening the valve when the rotary clutch part moves away from the other clutch part which occurs when the stock in the mixing chamber reaches a certain degree of density to provide a drag on the agitator blades, and a drive shaft having a gear thereon meshing with the first-mentioned gear.

MAXINE CHEVRIER.
